PORTABLE ILLUMINATED SIGN

Joseph R. Tabor, Chicago, Ill.

Application January 31, 1935, Serial No. 4,357

2 Claims. (Cl. 40—132)

This invention relates to a novel and useful illuminated display sign and has for one of its principal objects the provision of means whereby a light, durable and efficient display sign suitable for varied uses may be constructed economically and quickly.

An important object of the device of this invention resides in the provision of a box-like sign in a frame whereby the same may be readily assembled and made into a flat package for shipment or storage.

A further important object of the display sign of this invention resides in the fact that the entire housing may be assembled or disassembled without the use of clips, staples, glue or the like or without the use of special tools or skill.

Another and still further important object of this invention resides in the fact that the frame is constructed from a single piece of metal, and the housing from a single piece of cardboard.

Still another and further important object of the invention resides in the fact that the sign is so constructed as to allow of the use of some light material such as metal or the like, thereby providing a sign which is readily portable, yet rigid, sturdy and efficient.

Other and further important objects of the invention will be apparent from the disclosures in the accompanying drawing and following specification.

The invention, in a preferred form, is illustrated in the drawing and hereinafter more fully described.

In the drawing:—

Figure 1 is a perspective view of the illuminated display sign showing it in its preferred form.

Figure 2 is a plan view of the sign in knock-down condition, showing the same as viewed from the rear.

Figure 3 is a front plan view of the sign when knocked down.

Figure 4 is a larger plan view of the cardboard blank from which the housing is formed.

Figure 5 is a sectional view taken on the line 5—5 of Figure 3, looking in the direction indicated by the arrows.

Figure 6 is a sectional view on the line 6—6 of Figure 2, looking in the direction indicated.

As shown in the drawing:—

The reference numeral 10 indicates generally the frame of the improved sign of this invention, the same being preferably composed of metal in channelled shape and formed into rectangular or other desired figure as indicated or desired.

Adapted to cooperate with the frame 10 is a

housing formed of cardboard and which is composed of a back member 12, side elements 14, a top piece 16, bottom piece 18, a bottom securing member 20, and a sort of shelf or platform 22. These various components comprise an integral 5 whole, the parts of which are outlined and separated by scored lines or the like 24 whereby suitable bending is rendered apparent and easy.

The top member 16 is provided with integral 10 extensions or tabs 26 which fit into the channelled 10 frame 10 as indicated by the dotted lines in Figures 2 and 3. Such fitting retains the top of the housing in desired position when the device is assembled or set up.

The side elements 14 are provided with integral 15 flaps or extensions 28 separated from the main wing elements by scored lines as shown, and these extensions are adapted to be fitted into the side members of the channelled frame 10 below the tabs 26 when the device is in assembled position.

There is a contacting and interfitting relationship between the upper ends 30 of the extensions 28 and the lower edges of the extensions 26 when the housing is assembled with respect to the frame, and it will be noted that the projections 30 at the upper ends of the elements 28 are shaped 20 so as to produce an interlocking relationship with 25 corresponding projections and notches on the lower edges of the extensions 26. Accordingly, when the device is assembled, there is no possibility of the side members 14 becoming accidentally dislodged from position in the frame.

The integral extension or flap 20 on the bottom element 18 is provided with laterally extending 35 tabs 32 which, when the device is assembled, are fitted into position under the lower edge of the channelled frame 10 as best shown by the dotted lines in Figure 1.

At the lower end of the frame and on the inner 40 face thereof is an integral inwardly turned lip 34 (Figures 2 and 6) which, when the housing is set up, contacts the middle of the lower edge of the extension 20 preventing it with its extension 32 from sliding out of the channelled frame.

The ends 32 of the extension 20 are placed in 45 the lower ends of the side channels, and the part 20 rests on the lip 34. When the latter is withdrawn from the frame, it is lifted over the lip 34, and the ends 32 are pulled out of the channels.

The scored line 24 between the bottom element 18 and the shelf element 22 is such that when the device is set up, the shelf 22 will lie approximately in a horizontal plane, and this has an opening 36 therein for the seating of a lamp 55

socket or the like 38 which, in turn, supports a lighting globe 40. Openings 42 are provided in the shelf for ventilation purposes. Reinforcing plates 43 are fitted to the lower corners of the side extensions 14.

It will accordingly be seen that when the housing is set up and the tabs 26, 28, and 32 inserted into the channelled frame, the locking action of the in-turned lip 34 will retain the housing in the desired position with respect to the frame, thereby producing the device illustrated in Figure 1, the same including a transparent sign element or the like 44 which is composed of some suitable material such as paper, glass or the like, and which has imprinted or impressed thereon any desirable insignia, as, for example, a picture or a sequence of words or a combination thereof, the same being, of course, illuminated from behind by means of the light globe 40. Some means may be provided for flashing the light intermittently so as to render the sign more attractive, if desired.

Whenever it is desired to disassemble the sign for transportation or storage purposes, the element 20 with its extensions 32 is first released from the channel by lifting the same over the inwardly turned lip 34 which is at the open lower end of the frame. Pulling out of this element releases the bottom and at the same time allows of a withdrawal of the side elements 14 and their extensions 28 from the side channels of the frame. These elements are then folded into position over the back of the housing as best shown in Figure 3, after which the bottom 16 of the housing with its extension 20 is folded upwardly and rearwardly into the position shown in Figure 2. When folded, the top 16 is placed in the plane of the channelled frame, and the flange 26 remains in the channelled frame (Figs. 2 and 6). This reduces the entire housing to an assemblage of elements contained in a single plane whereupon the same can be conveniently packed for shipping or storage.

One of the novel features of this invention resides in the ease with which the transparent sign may be removed for purposes of change or the like. The same is simply pulled out of the channelled frame from the bottom in an obvious manner.

It will be obvious from the foregoing that herein is provided a display sign which, while being of sturdy and rugged construction, is also both light and economical.

Moreover, because of the light construction of the device of this invention, its use will be universal and not confined to places where a floor or staging are available as is required by the present type of display signs.

Furthermore, on account of the fact that it is so easily dismantled and requires but limited storage space, its use will not be confined to places requiring a permanent display sign, but it may be used also in places where its use is desirable only at intermittent periods.

It will be evident that this novel and useful device is so constructed that the sign displayed may be readily changed at intervals as desired, and the device may be used to display a series of pictures in such a manner as to give a comprehensive idea of the subject to be advertised. This series of pictures can be installed in the case, one at a time, having intervals of time intervening, and thus more clearly emphasize the subject matter. The display may also be so arranged so as to show several of these cases grouped together, telling the complete story at one time, and having a flasher arrangement so that only one of the cases will be lit at a particular moment, and thus have the story progress through the series to be shown.

The combination of a metallic frame with a cardboard housing and reflector provides a novel and useful element, the metallic member being made sufficiently light but strong, and the cardboard being of a material which will adequately withstand the most severe usage.

I am aware that many changes may be made and numerous details of construction varied throughout a wide range without departing from the principles of this invention, and I, therefore, do not purpose limiting the patent granted hereon otherwise than as necessitated by the prior art.

I claim as my invention:

1. A collapsible sign, including a rectangular frame, said frame being composed of channelled iron on three sides, and a unitary cardboard housing foldably connected with the rear of the frame, said housing comprising a back member, a top member, side members, a shelf member, and a bottom member foldably connected on score lines, the top and the side members having flanges insertable in the channel of the frame, the shelf member being foldably connected with the back member, and provided with means for mounting a lamp, the bottom member having a flange with extended ends insertable in the side members of the channelled frame.

2. A collapsible sign, including a three-sided channelled frame and a unitary housing foldably connected to the frame, said housing comprising a back member, a top member, side members, a shelf member, and a bottom member, all foldably connected on scored lines, flanges integral with the top and side members, the side member flanges being connected thereto by scored lines, and the top member flange connected along one line by a score line, and downwardly extending ears at the ends, said ears separated from the adjacent portions of the top member by cuts, complementary means on both the side member, flanges and the top member, and flanges for interfitting relationship when said flanges are inserted in the channel of the frame.

JOSEPH R. TABOR.
